COMBINED LAMP AND CANDELABRUM

Paul R. Glasgow, Ohio Soldiers Home,
Sandusky, Ohio 44870

Filed Dec. 23, 1969, Ser. No. 20,618

Term of patent 14 years

Int. Cl. D26—02

U.S. Cl. D48—20

FIG. 1

FIG. 2

FIG. 1 is a side elevation of a lamp embodying my new design.

FIG. 2 is a perspective view thereof.

The rear of the lamp base is flat and unornamented. The candles are shown in broken lines in FIGS. 1 and 2 for illustrative purposes only.

I claim:

The ornamental design for a combined lamp and candelabrum, as shown and described.
